UNITED STATES PATENT OFFICE.

PARIS R. FORMAN, OF CHICAGO, ILLINOIS, ASSIGNOR TO NATIONAL PNEUMATIC COMPANY, OF NEW YORK, N. Y., A CORPORATION OF WEST VIRGINIA.

DOOR-OPERATING MECHANISM.

Application filed April 25, 1917. Serial No. 184,363.

To all whom it may concern:

Be it known that I, PARIS R. FORMAN, a citizen of the United States, residing at Chicago, county of Cook, State of Illinois, have 5 made a certain new and useful Invention in Door-Operating Mechanism, of which the following is a specification.

This invention relates to door operating mechanism.

10 The object of the invention is to provide door operating mechanism, which is simple in structure, efficient in operation and economical in manufacture.

A further object of the invention is to 15 provide door operating mechanism, particularly adapted for use on cars, or the like, and which may be applied to cars already in use, with but little additional equipment.

A further object of the invention is to 20 provide a simple and efficient sliding door equipment for cars.

A further object of the invention is to provide a sliding door and means for operating the same, for cars on which no provision has 25 been made for doors of this nature in the construction of same.

Further objects of the invention will appear more fully hereinafter.

The invention consists substantially in the 30 construction, combination, location and relative arrangement of parts, all as will be more fully hereinafter set forth as shown by the accompanying drawing, and finally pointed out in the appended claims.

35 Referring to the drawing:—

Fig. 1 is a view in side elevation of door or gate operating mechanism embodying my invention.

40 Fig. 2 is a sectional view taken on the line 2—2, Fig. 1, and looking in the direction of the arrows.

Fig. 3 is an enlarged detail view of a portion of the structure shown in Fig. 2.

45 Fig. 4 is a sectional view taken on the line 4—4, Fig. 1; and looking in the direction of the arrows.

Fig. 5 is a top plan view of the door or gate structure shown in Fig. 1.

50 Fig. 6 is a view similar to Fig. 1, showing a modified arrangement of door or gate operating mechanism and control therefor.

Fig. 7 is an enlarged detail view of the door or gate control shown in Fig. 6.

Fig. 8 is a detail view of the motor control mechanism.

55

The same part is designated by the same reference character wherever it occurs throughout the several views.

It is among the special purposes of my present invention to provide a simple and 60 efficient equipment of door or gate and operating mechanism therefor, and particularly for structures such as cars, or the like, wherein no provision has been made for doors or gates, and operating mechanism 65 therefor.

As a concrete illustration, a great number of cars employed on the elevated roads of New York city are provided with swinging gates or doors, and no means are provided 70 to allow a sliding gate or door and control therefor to be installed. The swinging gates employed are well known in the art, and the disadvantages thereof have been recognized for years, chief among which being, 75 the space required for operation thereof, to open and close the same on the platform of the car. In other words, when the present gate is opened the platform of the car must be substantially vacant, so as not to obstruct 80 its path of travel. When the traffic is congested, and particularly during the rush hours of the day, this disadvantage has been magnified, making it awkward and at times practically impossible to operate the gates to 85 allow passengers to enter or leave the car, thereby greatly decreasing the comfort of the passengers, and the schedule and efficiency of the system.

As above stated, I provide a simple and 90 efficient means, requiring little additional equipment for converting gates and doors of this description to a sliding structure, easily and quickly controlled from the conductor's station, and obviating all of the 95 difficulties incident to the old type of swinging door or gate structures.

In the drawing, I show a stationary body at 1, which may be any structure, but which in the concrete illustration I have selected 100 to illustrate the principles of my invention, forms the end of the car body and which

contains the platform 2, the passage to and from the platform being controlled by the gate or door 3. The top of the gate or door 3 is provided with downwardly extending flange 5, which operates in an upwardly turned groove 6, formed by a bracket 7, suitably secured to the exterior wall of the stationary structure 1. It will be noted that the top 4 of the door or gate, is longer than the door itself, thereby insuring connection with the groove 6 of the bracket 7, even when the door is closed, as shown in Fig. 1. The bottom 9 of the door or gate is provided with loosely mounted wheels 10, which 10 operate on bracket 11, suitably carried by bracket 12, secured to the structure 1. Pivotally secured to the body or structure 1 at 13 is an arm 14, pivotally secured at 17 to the rear end of the door 3. Pivotally secured to the arm 14 at a point 19, above its fulcrum 13, is an arm or lever 20, which arm or lever is connected to a lever 21, secured to one end of the shaft 22, the other end of which shaft is secured to a lever 23, connected to a vertical lever 24, which is connected to one end of the bell crank lever 25, the other end of the bell crank lever being connected by a rod 26, to one end of the bell crank lever 27, the other end of which bell crank lever 27 forms the operating handle 28. Thus to open the door from its position, as shown in Figs. 1 and 2, the handle 28 is depressed counter clockwise, thereby rocking the respective arms and levers to 30 push the rod 20 to the right, (see Fig. 1), thereby forcing the arm 14 clockwise about its fulcrum 13, and thus drawing the door to its open position, as indicated in dotted lines, the opening movement thereof being 35 facilitated by its rolling connection with the rail 11, and its sliding groove connection in the bracket 7. To close the door, a reverse operation of the handle 28 exerts a pull upon the rod 20, which pulls the arm 14 about 40 its pivotal fulcrum 13, thereby causing the door to roll on the rail 11.

When the door is in its complete closed position as shown in full lines by Fig. 1, I provide means for preventing the door or gate from swinging about its connection in the bracket 7 and from being sprung or otherwise bent to thereby interfere with its sliding connection in said bracket 7. In the form shown, this consists of a reinforcing 45 suitable brace 30, suitably secured to the stanchion 31, located on the car platform, as shown best in Figs. 1 and 5. This brace 30 forms a rest for the door in its extreme closed position, to prevent the end or further edge of the door or gate from being pushed 50 downwardly when in its closed position.

It will be seen from the foregoing that I have provided an exceedingly simple manually operated sliding door mechanism, 55 which door and its support and operating

means are all located to the exterior of the car, and consequently require no alteration in the car structure, nor the addition thereto of means for accommodating the door or gate. It will be understood that my invention is not to be limited however, to a manually operated door as any means may be employed for controlling the movement of the door or gate. For example in Figs. 6 and 7, I show my invention as applied to a door operating mechanism controlled by a fluid pressure motor. In this construction the essential features of the door or gate are identical with that described in connection with Fig. 1, the change being that, on the car body in the usual location, I mount a fluid pressure motor of standard type, indicated generally at 40, the arm 41 of which is connected by a rod 42 to the gate 3. The valve indicated generally at 44 is controlled by a suitable rod 45, connected to a lever 46, passing through the floor 47 of the car body, which lever is secured to one end of a rod 48, the other end of which is secured to a vertically extending rod 49, provided at 50 its end with the operating handle 50. The rod 49 is carried by a suitable sleeve 51 secured to the car. Operation of the valve 44 of the motor and consequently of the motor itself is secured by the manual rocking of the handle 50 which thereby shifts the valve 44 through the respective levers and lengths 45, 46, 48 and 49, as will be readily understood and as shown in the drawing the operation of the valve causes 55 the motor to operate the arm 41, to open or close the door or gate 3, according to the direction of twist imparted to the rod 49 by its associated handle 50.

While I have shown and described specific structural features particularly desirable to the specific use at present contemplated, I wish it to be clearly understood that my invention in its broad scope is not to be limited thereto, as many modifications and details will readily occur to those skilled in the art without departing from the spirit or scope of my invention, as defined in the claims.

Having therefore set forth the objects and nature of my invention and having shown and described one application thereof, what I deem new and useful and of my own invention and desire to secure by Letters Patent is,—

1. The combination with a car body of a bracket carried by the exterior wall of said car body, a door provided with a flange extending the length of its top edge and beyond the rear end of said door, and engaging said bracket, and means for slidably moving said door and flange in said bracket to open and close said door.

2. The combination with a car body of a bracket carried by the exterior wall of said

car body, a door provided with a flange extending the length of its top edge and beyond the rear end of said door, and engaging said bracket, and means for slidably moving said door and flange in said bracket to open and close said door, and a brace carried by the car body for holding the front

edge of said door when said door is in its closed position.

In testimony whereof I have hereunto set 10 my hand on this 14th day of April A. D., 1917.

PARIS R. FORMAN.
